UNITED STATES PATENT OFFICE.

ROBERT M. SULLY, OF PETERSBURG, VIRGINIA.

SEAL-LOCK.

SPECIFICATION forming part of Letters Patent No. 341,779, dated May 11, 1886.

Application filed February 13, 1886. Serial No. 191,833. (No model.)

To all whom it may concern:

Be it known that I, ROBERT M. SULLY, a citizen of the United States, residing at Petersburg, in the county of Dinwiddie and State of Virginia, have invented certain new and useful Improvements in Seal-Locks for Cars; and I do hereby declare the following to be a full, clear, and exact description of the invention, such as will enable others skilled in the art to which it appertains, to make and use the same.

My invention relates to seal-locks for freight-cars and the like; and it consists in providing simple and efficient means whereby an ordinary tag, such as is employed for a shipping-tag, may be used as a seal without the necessity of a separate metallic or other sealing appliance.

With my construction of lock, when the sealing-tag has once been applied, it will be impossible to withdraw the bolt without breaking or destroying the tag; and the condition of the tag will always indicate unmistakably whether the lock has been tampered with.

The particular construction in which I have embodied my invention is illustrated in the accompanying drawings, in which—

Figure 1 represents a portion of a car with my improved lock applied thereto. Fig. 2 is a side elevation, partly sectional, of a detached portion of my lock; and Fig. 3 shows one form of tag which I use as a seal.

Referring to Fig. 1, A represents an ordinary freight-car, and B the door of the same, adapted to slide back and forth in the usual manner. b b are shoes secured to the car-door, and a a are the rails along which the door slides. The hasp C is secured to the car-door in the usual way, the lock itself being bolted to the door-frame, as shown at D.

The details of the lock are best illustrated in Fig. 2, E being the staple over which the hasp C is adapted to fit, and F being the bolt of the lock. The bolt is adapted to slide in openings g and h in the posts G and H, respectively, the opening in post G being just large enough to fit loosely around the bolt, and that in the post H being somewhat larger, for a reason that will be hereinafter explained.

The post G is provided with a second opening, m, which extends from the opening g longitudinally through the post and is closed by

a countersunk screw, n. Within the opening m is a catch, e, which is pressed out by a spring, s, against the bolt F, in the vertical opening g. The catch is prevented from turning on its longitudinal axis by a rod or pin, k, which passes through the opening and through a slot, o, in the body of the catch.

The bolt F is provided with two notches, i i, on opposite sides, with one or the other of which the catch e will engage when the bolt is in its locked position. The bolt can, however, be pushed downward without being interrupted by the catch e by turning it so that either of the sides not notched shall pass over the catch. In like manner the bolt can be released from engagement with the catch by turning it a quarter of a revolution, after which it can be pushed down into the position shown in Fig. 2 for receiving the sealing-tag. The tag is applied to the hook t on the lower end of the bolt, and the bolt and tag are then drawn upward until the latter has entered the slits w w in the post H, and one of the notches i i has come into engagement with the catch e. Now, one of the notches i i is on the same side of the bolt as the hook t. There being two notches i i, on opposite sides of the bolt, it can be drawn into the locked position with either surface of the tag exposed to view. To facilitate the same end, about half the body of the bolt is cut away just above the hook.

It is evident that when the bolt is once locked by the catch and the sealing-tag is in place, the bolt cannot be withdrawn without breaking the tag, and thereby betraying the fact of such withdrawal.

To avoid the danger of losing the bolt and thus destroying the lock, I pass a ring, r, through the upper end of it and braze or weld the ends of this ring together so as to make it solid. I also make the hooked end of the bolt too large to pass through the opening g, though it will slide through the opening h with little or no friction.

As a sealing appliance, I may use a tag similar to the ordinary shipping-tag. This tag may be marked, as indicated in Fig. 3, with the name of the railroad company which is responsible for the car and its contents, the shipping-point, the character of the contents, and the destination of the car. It may also be provided at either side with columns of fig-

ures representing the days of two or more successive months, with blanks at the top for the names of the months. I prefer to have the numbers printed or otherwise applied to the tag in regular order from 1 to 31 in the left-hand column, and in reverse order from 31 to 1 in the right-hand column. By punching the proper numbers each conductor can indicate the days on which the car came under and left his charge. The distinctive character of the punches employed by various conductors will ordinarily be a sufficient indication as to which one, if any, is responsible for delay or injury to the car or its contents. The matter that is shown on the tag, however, can obviously be varied at will to suit varying needs without departing from the spirit of my invention; nor do I wish it understood that I confine myself to the use of a tag constructed like the ordinary shipping-tag, as I may employ a metallic tag or any other that is formed into a thin sheet.

Having now described my invention, what I claim, and desire to secure by Letters Patent, 25 is—

1. In a seal-lock for cars, the locking-bolt and a fastening device formed thereon to pass through a perforation in a seal, in combination with a post having a receptacle which encloses the bolt and fastening device, together 30 with the attached seal, when the bolt is in locked position, substantially as set forth.

2. In a seal-lock for cars, the combination, with the bolt F, provided with the hook t and the notch i, of the posts G and H, the slits w 35 w, and the catch e, substantially as and for the purpose set forth.

3. In a seal-lock for cars, the bolt F, the posts G and H, the openings g and h, the enlarged hooked portion t, and the ring r, substantially as and for the purpose set forth. 40

In testimony whereof I have affixed my signature in presence of two witnesses.

ROBERT M. SULLY.
